**METHOD AND APPARATUS FOR FORMING
SOCKET-HEAD CAP-SCREW BLANKS**

Herbert L. McClellan and Donald E. Huss, Tiffin, Ohio,
assignors to The National Machinery Company, Tiffin,
Ohio, a corporation of Ohio

Filed Sept. 17, 1962, Ser. No. 223,962
11 Claims. (Cl. 10—24)

This invention relates generally to forging, and more particularly, to a novel and improved method and apparatus for cold forging articles having upset portions such as socket-head cap-screws and the like.

In the manufacture of socket-head cap-screws, it has been customary to shear blanks from stock and then upset and pierce the cap-screw blank to form the socketed head and shank. The blank is then generally machined on both the head and shank end and threaded to complete the cap-screw. The machining or facing of the head of the blank has been used to form the chamfer at the edges, maintain head height within the required tolerances, remove the tapered section of the hex hole, and to provide an improved finish on the head surface for appearance and for safety since such facing removes any sharp edges.

The machining of the shank end of the blank has been performed in a pointer as one of the operations of a combined machine incorporating heading, pointing and thread-rolling but the facing operation at the head end has generally required separate handling and the provision of a separate machine to perform this function. With such machining, difficulty has sometimes occurred since the cutting operation often leaves a burr at the hex hole in the head. This separate facing operation has created additional machine investment, expense of maintenance and operating costs as well as providing difficulties, as an example, in the chucking of the screws without damaging the thread and accurate positioning of the blanks so that the machining operation will be properly performed.

In addition, the cost of material has been increased since the facing off or scraping on a $\frac{3}{8}$ " cap-screw removes as scrap about $\frac{1}{32}$ " of material. In high production manufacture, the accumulative cost of such scrap is substantial.

The need of machining the head end of the blank has often been created by the occurrence of islands on the ends of the initial blank sheared from wire stock which produce sharp edges and flaws in the headed end of the blank. These islands which constitute small projections partially severed from the piece to which they are joined, leave sharp edges at the completion of the heading operation which can snag or cut the user's fingers and which detracts from the appearance of the finished product.

In the method and apparatus incorporating this invention, an improved shear is provided for cutting the initial blanks from the wire or rod stock without forming islands or excessive unevenness in the end or cut-off surfaces. The ends, however, of such initial blanks are not square. In the first forming operation, the blanks are positioned in die assemblies and coned in a manner which concentrates the pressure on the end face of the blank to provide complete squaring of the end. The dies and tools at this step in the operation are also arranged to prevent twisting, bending or eccentric movement of the blank.

The blank is thereafter upset, forming a head having a smooth end face and a well filled crown around the outer edges thereof. Here again, the dies and tools of upsetting are arranged so that the pressure is concentrated on the end face so that a good finish and close tolerance results. The inner end of the headed part does not flow into the corners of the die cavity, leaving unfilled corners which are filled in the next operation.

In the final forming operation, the head is pierced with

2

a polygonal punch or socketing tool. During the first portion of punch penetration, the material of the head is upset forward into the lower corners of the die cavity to form a sharply filled head. This forward upsetting results in a cutting in of the punch from the end face and does not produce distortion of the crown or end face. As soon as the lower corners of the head are sharply filled the pressure builds up causing backward extrusion of the head along the punch and die, thereby completing the finished blank.

Because the cut-off is performed without creating islands on the sheared face, a high quality finish is produced without sharp cutting edges on the end face. The shearing also accurately provides the proper volume of material so tolerances are accurately maintained without a finishing or facing cut on the head. As a result, the finished cap-screw can be formed in a single combined machine having a progressive header, a pointer for machining the shank end of the blank and a thread roller for producing the required threads on the shank. Such a combined machine is of the general type disclosed in the United States Patent to Frost, No. 2,020,658 dated November 12, 1935.

It is an important object of this invention to provide a novel and improved method and apparatus for forming high quality socket-head cap-screw blanks without requiring a machining operation to finish the head face of the blank.

It is another object of this invention to provide a novel and improved method and apparatus for shearing blanks from cylindrical rod or wire stock having a clean, well-defined cut without islands or other surface defects.

It is still another object of this invention to provide a method and apparatus for shearing cylindrical blanks from wire or rod stock wherein the sheared ends are free from substantial surface defects in combination with an upsetting operation to square the end of such blank to form a smooth and square end face.

It is still another object of this invention to provide a novel and improved method and apparatus for forming socket-head cap-screws wherein means are provided to trap a predetermined amount of lubricating oil at the end of the socketing tool for the lubrication thereof during the socketing operation.

It is still another object of this invention to provide a novel and improved method and apparatus for forming socket-head cap-screws having a chamfer adjacent to the end of the socket and a crowned outer edge on the socket end of the head without machining.

It is still another object of this invention to provide a novel and improved apparatus for shearing a blank from rod or wire stock wherein the shear is provided with spacing between the cutter knife and quill to prevent the occurrence of islands or deep surface imperfections combined with a squaring operation producing a smooth and square end on the blank.

It is still another object of this invention to provide a novel and improved method and apparatus for forming socket-head cap-screw blanks wherein a shallow recess is formed in the end of the blank during the heading operation and a socketing tool is thereafter pressed into said recess to form the required socket in which the recess and socketing tool are proportioned and arranged to provide for the trapping of a predetermined amount of lubricating oil for the lubrication of the end of the socketing tool.

It is still another object of this invention to provide a novel and improved stripper for shaping the end of a blank and also stripping the blank from a tool.

It is still another object of this invention to provide a novel and improved die mounting providing preloading at one surface greater than the preloading at other sur-

faces to insure that blanks formed therein do not distort the die and form tapered articles.

Further objects and advantages will appear from the following description and drawings, wherein

FIGURE 19 is a side and end view of the final blank formed in the third die station.

Referring to FIGURE 1, the numeral 10 designates a bed frame of any suitable design. A main crankshaft 11 is journaled on the opposite sides of the bed frame and is provided with a crank 12 having a connecting rod 13 journaled thereon. A countershaft 14 is geared to the crankshaft 11 for rotation at the same speed as the crankshaft. The bed frame is provided at its forward end with a die breast 16 and within a slideway formed in the frame a header slide 17 is mounted to reciprocate toward and away from the die breast 16. The connecting rod 13 is pivoted on the slide to produce the reciprocation thereof in response to crankshaft rotation.

Wire or rod stock 18 is fed through the bed frame 10 by conventional type feed rollers or the like and is sheared

at a shearing station 19 into blanks 21 illustrated in FIGURE 16 and transferred to the first die station 24. Referring to FIGURE 2, the stock is engaged by a shear including a vertically reciprocable knife assembly 22 which shears off the blank 21 and carries it upward into horizontal alignment with the blank working stations 5 which wherein it is gripped by a first pair of transfer fingers 23. A knockout (not shown) is used to push the sheared blank 21 from the vertically reciprocating knife 22.

The transfer mechanism is arranged to simultaneously carry blanks from the shear to a first die station 24, from the die station 24 to a second die station 26, from the second die station 26 to a third die station 27 and from the third die station 27 to a blank receiving station 28. Transfer fingers 23 are mounted on a carriage 29 which reciprocates horizontally back and forth in front of the die breast to accomplish this action. The fingers 23 are operated to grip blanks ejected from the dies and progressively position the blank in front of the next die station for the subsequent operation. The entire transfer system is powered in timed relationship to the movement of the header slide so that blanks are progressively moved to each of the die stations and to the blank receiving station 28. The structure illustrated for transferring the blanks progressively to each blank working station is disclosed in detail in the United States patent to Clouse, No. 2,026,823 dated January 7, 1956.

Wire stock 18 is fed through the die breast 16 at the shearing station 19 by conventional feed rollers until it 30 engages an adjustable stock gauge 31. When the stock 18 engages the gauge 31, the proper volume of stock necessary to form the finished bolt blank is sheared from the stock by vertical movement of the knife 22.

Referring to FIGURES 3 through 5, a hardened quill 32 is mounted in a bore 30 in the die breast 16 and is formed with a bore 33 through which the stock 18 extends. A hardened cutter ring 34 is mounted on the knife 22 and is formed with a similar bore 36 aligned with the bore 33 when the knife 22 is in the lower position illustrated in FIGURE 2. After the forward end of the stock engages the stock gauge 31, the knife 22 carries the cutter ring 34 upward shearing the blank 21 from the stock 18.

In order to prevent the formation of islands in the cut 45 end of the blanks 21 or other drastic surface irregularities, the end of the quill 32 is formed with curved cutting edge 37 extending back from the end face of the quill 32. Similarly, the cutter ring 34 is formed with a curved cutting edge 38 extending back from the face of the cutter ring 34. With this structure, the cutting edges 37 and 50 38 are spaced apart the greatest distance in the zone where the greatest thickness of material must be sheared. Since the stock is cylindrical, the thickness sheared is greatest along a plane through the axis of the stock parallel to the direction of shearing movement of the cutter ring 34. The depth of the zone to be sheared decreases at points laterally spaced from this plane.

To form the curved cutting edges 37 and 38 on the quill 32 and cutter ring 34 respectively, their faces are 60 ground with a formed grinding wheel thereby producing a shallow curved recess 40 extending across the quill and cutter ring. This recess 40 in the cutter ring 34 is best illustrated in FIGURE 4. The curved cutting edges are formed by the intersection of the bores 33 and 36 and curved recess 40 and have a projected shape on a plane through the axis of the bores 33 and 36 and perpendicular to the direction of cutter ring movement as illustrated in FIGURE 3.

The quill 32 and cutter ring 34 are mounted so that 70 their respective recesses 40 extend parallel to the line of cutter ring movement. The quill 32 is adjustable axially in the bore 30 to provide adjustment of the running clearance to about ".004" between the face of the cutter and the face of the quill. Any suitable means, such as a set screw 30a, may be used to lock the quill in its adjusted

position. The spacing between the cutting edges 37 and 38 is determined by the ductility of the stock. Stock which has greater ductility requires a greater spacing between the cutting edges 37 and 38 which is achieved by grinding of both the cutter and quill.

Referring to FIGURE 5, as the cutter ring 34 moves upwardly relative to the quill 32, the upper portion 37a of the cutting edge 37 (indicated by a dotted line) cuts into the upper part of the stock 18. Similarly the lower portion 38a of the cutting edge 38 cuts into the lower side of the stock 18. This cutting or shearing of opposite sides of the stock 18 continues until the condition illustrated in FIGURE 5 is reached. At this point in the shearing operation, the unsheared section ruptures along the dotted line 45 connecting the portions 37a and 38a. This line or plane of rupture is inclined relative to the direction of shearing force and tends to approximate the natural plane of rupture determined by the material properties of the stock 18.

The axial spacing between the cutting edges is developed by grinding the quill and cutting ring until the angle of the plane of rupture 45 approaches the natural angle of rupture of the material. When this condition is reached the material of the stock ruptures cleanly along a single plane and islands or excessive surface imperfections are eliminated. This also results in greater uniformity of blank volume.

The curved forms of the cutting edges 37 and 38 results in axially projecting portions 37b and 38b respectively, at the sides of the recesses 40. These projections form a curved profile in the sheared portion of the cut which generally follows the inclined rupture plane to insure that the rupture surface will be clean across the entire end of the blank. The forward ends of the projecting portions 37b and 38b are however, axially spaced from each other so that clearance is provided to prevent wiping damage to the rupture surface as the cutter ring 34 continues to move to its upper position.

The blank 21 is carried by the transfer fingers 23 from the shearing station 19 to the first die station 24 illustrated in FIGURES 6 and 7. Mounted in the die breast 16 at the first die station 24 is a die holder 46 which in turn supports an extrusion die 47. The extrusion die 47 is formed with an entry portion 48, having a diameter substantially equal to the diameter of the blank 21, leading to an extrusion throat 49 with a diameter equal to the required shank diameter of the bolt. A knockout pin 51 is positioned with its end 52 engageable with the inner end of the blank when the proper amount of blank material is extruded through the extrusion throat 49. Engagement of the end of the blank with the end face 52 of the knockout pin 51 prevents further inward movement of the blank through the extrusion throat 49 and also operates to provide some squaring of the end face of the blank.

Mounted on the header slide 17 is a sliding sleeve die 53 supported for axial movement relative to the header slide 17 within a bearing sleeve 54. A key 56 mounted in the header slide 17 extends into an elongated keyway 57 and operates to limit axial movement of the sliding die 53 relative to the header slide 17 in a direction toward the die breast 16. A spring 58 extends between a backup plate 59 and a shoulder 61 to bias the die sleeve 53 toward the forward extreme position of its travel relative to the header slide 17 as illustrated in FIGURE 6. The sliding die 53 is formed with a conical coning section 62 extending back to a coaxial bore 63. An upsetting tool 64 extends into the bore 63 with a close fit for lateral support and is formed with an enlarged head 66 engageable with a shoulder 67 in the sliding die 53 to limit forward movement of the upsetting tool 64 relative to the sliding die 53. A backup pin 68 extends between the rearward end of the upsetting tool 64 and the backup plate 59 to limit rearward movement of the tool 64 and transmit the upsetting loads to the header slide 17.

The upsetting tool 64 is formed with a flat end face 69 engageable with the end of the blank 21 positioned

at the die station 24 as the header slide 17 moves toward the die breast 16. The bore 63 in the sliding die 53 has a diameter substantially equal to the diameter of the blank 21 so that it provides substantial lateral support for the outer end of the blank preventing bending of the blank or the like during the extrusion of the inner end through the extrusion throat 49. As discussed above, the ends of the blank 21 are formed with a clean-cut which, however, is not square. Therefore, initially the engagement between the end face 69 and the end of the blank 21 is eccentric and would produce bending of the blank if it were not for the lateral support of the bore 63 of the sliding die 53.

As the header slide 17 moves toward the die breast 16, the sliding die 53 is maintained in its forwardmost position by the spring 58. Therefore, the blank is well supported at it is pushed through the extrusion throat 49 until its inner end engages the end face 52 of the knockout pin 51.

FIGURE 6 illustrates the position of the various elements at the point in the stroke when the forward end of the sliding die 53 engages the face of the die 46 preventing further forward movement of the sliding die 53. The sliding die is formed so that the coning section 62 is spaced from the end of the extrusion die 47. The continued movement of the header slide 17 toward the forward dead center position illustrated in FIGURE 7 continues to carry the upsetting tool 64 forward causing the blank to move along the sliding die 53 and extrusion die 47 until the inner end engages the end face 52 of the knockout tool 51. Such engagement prevents further forward movement of the blank and initiates the upset in the coning section 62 of the sliding die 53.

The upsetting of the end of the blank occurs while the sliding die 53 is stationary with respect to the die breast 16 so the upsetting requires movement of the end of the blank relative to the coning section 62 of the sliding die. Friction between the walls of the section 62 and the bore 63 resists such forward movement and results in a high pressure between the end of the blank and the end face 69 of the upsetting tool 64. This produces a pressure concentration which assures that the end face 72 of the blank 73 formed in the first die station 24 is ironed out and is smooth and square as illustrated in FIGURE 17. The radial confinement of the stock in the sliding die 53 produces a well-filled cone blank wherein the blank 73 is symmetrical about its central axis.

As the header slide 17 moves back from the die breast 16, the knockout pin 51 is pushed forward by a knockout drive 74 illustrated in FIGURE 1 to eject the blank 73 from the die 47. Transfer fingers 23 grip the blank 73 as it clears the die 47 and carry the blank into a position in alignment with the second die station 26 illustrated in FIGURE 8.

Mounted in the die breast 16 at the second die station 26 is a die holder 76 formed with a converging tapered shoulder 77 engaging and supporting a die insert 78 having an external taper matching the taper of the shoulder 77. Positioned behind the die insert 78 is a second die insert 79 which is laterally supported in a bore 81 formed in the die holder 76. Rearwardly of the second die insert 79 is a tubular thrust member 82 pressed against the rearward end of the second die end insert 79 by a mounting ring 83. The mounting ring 83 is threaded into the inner end of the die holder 76 and is formed with an end face 84 bearing against a shoulder 86 on the thrust member 82. The rearward end of the mounting ring 83 engages a backup plate 87 which, in turn, transmits the upsetting forces to the frame of the machine.

The first die insert 78 is formed with a central bore 88 which cooperates with an end face 89 on the second die insert 79 to define a head cavity in which the head of the blank is upset. Extending rearwardly from the end face 89 the second die insert 79 is formed with a through bore 91 coaxial with the bore 88 and also aligned with a bore 92 extending through the thrust member 82. The

bore 91 and 92 have a diameter substantially equal to the diameter of the extruded portion of the blank 73 so that the blank 73 slides easily into the dies prior to the upset. A knockout pin 93 extends into the bore 92 and is positioned with its end face 94 engageable with the inner end of the blank 73 when the extruded portion of the blank 73 is positioned within the bore 91 and bore 92 and the unextruded portion extends forward of the end face 89. A plurality of vent grooves 95 are symmetrically arranged in the die insert 78 to prevent entrapment of lubricating oil or air at the inner corner of the cavity formed by the bore 88 and face 89.

Mounted on the header slide 17 at the second die station 26 is a tool holder 96 which supports an upsetting tool ring 97 in alignment with the first die insert 78. Positioned behind the tool ring 97 is a backup plate 98 which transmits the upsetting loads to the tool holder 96. The tool holder 96 in turn transmits the upsetting loads through a second backup plate 99 to the header slide 17. The tool ring 97 is formed with a central bore 101 having a diameter slightly larger than the distance across the corners of the socket ultimately formed in the blank. Positioned within the bore 101 is an indenting pin 102 formed with an end face 103 in the shape of a truncated cone with an angle of about 80° to the axis of the pin and symmetrically arranged air vents 100 on its outside diameter parallel to its axis. These vents 100 communicate with vent grooves 100a in the backup plate 98. The end face is flat at 104 to a diameter of about 0.04 of an inch in the size machine illustrated. The indenting tool operates to form a chamfer 106 which remains in the finished blank and assists in guiding a wrench into the socket formed in the next operation.

The tool ring 97 is formed with a recess 107 having a rounded corner at 108. The rounded corner 108 forms the required crown edge on the upper end of the finished head.

As the header slide 17 moves toward the die breast 16, the blank 73 positioned at the second die station 26 is engaged by the indenting pin 102 and pushed into the dies until its inner end engages the end face 94 of the knockout tool 93. This prevents further inward movement of the blank. Continued movement of the header slide toward the die breast causes the end of the blank to be upset to the condition illustrated in FIGURE 8 wherein the initial headed blank 109 illustrated in FIGURE 18 is formed. The blank 109 has a straight shank 111 and a head portion 112. As the head portion 112 is upset into engagement with the wall of the bore 88, a friction resisting inward movement of the blank material is developed which again produces increased pressure on the upper face resisting further upsetting. Therefore, the upper face of the blank is smoothly polished and a rounded corner at 113 is formed. Also, the indenting tool 102 forms the shallow recess 114. The corner 116 is not sharply filled since higher pressures are required to flow material into sharp corners particularly when the resistance due to frictional engagement with the cavity wall resists such flow.

As the header slide 17 moves back from the die face, the knockout pin 93 is pushed forward by the knockout drive 74 to eject the blank 109 from the dies. Transfer fingers 23 grasp the blank 109 and move it to the third die station 27 wherein the finished blank 117 is formed.

Mounted in the die breast 16 at the third die station 27 (illustrated in FIGURES 9 and 10), is a third die holder 121. The die holder 121 is formed with an inwardly extending flange 122 having a conical inner face 123 engaging a conical outer face 124 on a first die insert 126. The included angle of the conical outer face 124 is about 1° less than the included angle of the conical inner face 123. This difference in angle provides more press at the face of the first die insert 126 and more forcibly restrains the insert against expansion at the face. The lower corners of the die cavity are also vented by grooves

135 to prevent the entrapment of air or lubricating oil. The venting at the lower corner results in a sharp corner at the bottom of the head and a flat surface on the under side or bearing surface of the screw head. The higher preload adjacent to the face of the die results in a constant diameter on the head from top to bottom.

Positioned behind the first die insert 126 is a second die element 127 laterally supported in a bore 128 in the die holder 121. Inward from the second die element 127 is 10 a tubular thrust member 129 which is clamped in position by a mounting ring 131, threaded into the die holder 121. The forward end of the thrust member 129 engages the 15 rearward end of the second die element 127 clamping it in position against the inner face of the first die element 126 and in turn holds the first die element 126 against the 20 conical inner face 123. The end of the mounting ring 131 seats against a shoulder 132 in the thrust member 129 and the rearward end of the mounting ring is seated against the backup plate 87. Therefore, the forming loads are transmitted through the thrust member 129 and the mounting ring 131 to the backup plate 87.

In the illustrated embodiment, the blank is of the type which is threaded for only a portion of the shank length. Therefore, an extrusion die 133 is mounted at the forward 25 end of the thrust member 129 and is formed with an extrusion throat 134 which reduces the diameter of the shank in the area to be threaded so that the thread rolled on the shank will have a maximum diameter equal to the diameter of the unthreaded portion of the shank. The 30 end face 136 of the second die insert 127 cooperates with a bore 137 to define a die cavity in which the head is formed. The second die element 127 is formed with a through bore 138 coaxial with the bore 137 and also coaxial with the extrusion throat 134. The tubular thrust member 129 has a bore 139 coaxial with the extrusion throat 134 and formed with a diameter slightly larger than the diameter of the extrusion throat. A knockout 35 pin 141 is positioned with its forward end 142 in the bore 139 and engageable with the end of the shank of the blank when the proper amount of extrusion through the extrusion throat 134 is completed.

A tool holder 143 is mounted in the header slide 17 at the third die station 27 and is formed with a central bore 144 which laterally supports a punch holder 146. 45 Mounted within the punch holder 146 is a piercing or socketing tool 147 formed with an enlarged rearward end 148 engageable with a shoulder 149 in the punch holder 146 to prevent forward movement of the piercing tool relative to the punch holder 146. The rearward end of 50 the enlarged end 148 seats against a backup pin 151 which is in turn seated against a thrust member 152 mounted in the header slide 17. A wedge 150 adjustably locates the thrust member 152. The forward end of the 55 piercing tool 147 is formed with a hexagonal end portion 153 with a conical truncated cone 154 at its forward face.

Because the lower corners 116 of the blank 109 are unfilled, the first action which occurs at the third die station 27 as the piercing tool 147 enters the head is forward upsetting causing the metal of the head to flow 60 into the corners sharply filling the lower corners of the head. As a result, the piercing tool 147 cuts into the head past the rounded corners 113 and does not change the contour of the upper face of the head. FIGURE 9 illustrates the positions of the elements at the end of this 65 forward upsetting phase.

As soon as the lower corners are sharply filled, continued movement of the piercing tool 147 into the head, causes backward extrusion along the hex portion 153, thus increasing the height of the finished head to that shown in 70 FIGURE 10. Since the initial portion of the piercing operation does not produce lateral forces, the chamfer around the hexagonal socket at the upper face of the finished bolt remains undisturbed.

When manufacturing socket-head cap-screws which do 75 not require the chamfer around the open end of the

socket, the diameter of the indenting tool 102 may be reduced to a diameter no greater than the diameter across the flats of the hexagonal portion 153 of the piercing tool 147.

Referring to FIGURES 11 and 12, the angle of the truncated cone of the piercing tool 147 is less than the angle of the cone 103 of the indenting pin 102 so that lubricating oil will not be trapped by the piercing tool adjacent its outer edges. However, the flat end face 156 illustrated best in FIGURE 12 has a diameter greater than the corresponding flat end face of the indenting pin 102 so that a small controlled size pocket 155 is provided to entrap lubricating oil as the piercing tool enters the head. This entrapped lubricating oil serves to lubricate the end of the piercing tool during the piercing operation and thereby increasing the tool life. It is important to insure that the correct amount of lubricant is entrapped since insufficient amounts of lubricant produces excessive punch wear and excessive lubricant causes radial lines at the inner end of the socket which are ragged, detracting from the appearance of the finished article and producing stress concentrators. The pump and nozzle for delivering the lubricant to the tool and dies has not been shown since they are well known in the art.

As the header slide 17 moves back after the completion of the work stroke at the die station 27, the knockout punch 141 is pushed forward by the knockout drive 74 to eject the finished blank from the dies at the third die station 27.

A stripper mechanism illustrated in FIGURES 9, 10, 13 and 14 is provided to perform the combined functions of stamping, lettering or numbering on the upper surface of the head of the cap-screw blank around the socket and also strip the blank from the socketting tool 147 as the header slide 17 moves back from the die breast 16. The stripping mechanism includes a stripper ring carrier 161 supporting a stripper ring 162. The carrier 161 is slidably supported by push pins 163 guided in bearings 164 mounted in the tool holder 143. The push pins 163 are anchored in the carrier 161 against a shoulder 166 by mounting bolts 167 threaded into the ends of the push pins 163. The views of FIGURES 9 and 10 only illustrate one push pin 163 and mounting bolt 167 since these views were taken along a broken plane section arranged to also illustrate the spring mechanism for resiliently urging the stripping mechanism toward the rearward position. However, two symmetrically arranged push pins 163 and mounting bolts are provided on opposite sides of the carrier as illustrated in FIGURE 14.

To urge the carrier 162 toward the rearward position illustrated, spring bolts 168 symmetrically arranged as illustrated in FIGURE 14, project through the carrier 161 into axially extending bores 169 formed in the tool holder 143. Nuts 171 are threaded onto the ends of the bolts 168. Springs 172 extend between the nuts and face plate 173 mounted on the forward face of the tool holder 143 by bolts 174 and operate to resiliently bias the carrier 161 and stripper ring 162 toward the rearward position illustrated.

The stripper ring 162 is moved forward relative to the header slide 17 into engagement with the upper face of the blank 117 at two separate times in the cycle and performs two separate functions. The first function is to stamp any desired marking on the upper face of the blank head around the socket and the second is to strip the blank from the socketting tool 147. Referring to FIGURE 14, the stripper ring 162 is formed with raised lettering which stamps the desired figures or lettering on the head of the blank.

In FIGURE 13, the mechanism for moving the stripper ring 162 forward is illustrated. The rearward ends of the push pins 163 engage the forked upper end of a stripper lever 175 pivoted at 176 on the header slide 17. The rearward side of the lever 175 seats against an anvil 177 slidably mounted in a hollow cylinder 178 mounted in a

bore 179 in the header slide 17. The anvil 177 is formed with a flange 181 engageable with the forward end of the cylinder 178 to limit rearward movement of the anvil 177. Slidably located in the cylinder 178 is an impact piston 182 closely fitting the inner wall of the cylinder, a spring 183 extends between the piston 182 and anvil 177 normally maintaining the piston in the rearward position illustrated in FIGURE 13. A spring guide 184 is mounted on the anvil 177 to prevent buckling of the spring 183.

Air under pressure is supplied through any suitable valve (not shown) to inlet passage 186 formed in the header slide 17 to the rearward end of the bore 179. The cylinder 178 is formed with an annular recess 187 communicating between the passage 186 and radial ports 188 extending through the cylinder walls. Seals 189 on the cylinder 178 engage the inner wall of the bore 179 to prevent leakage therealong. When air under pressure is admitted through the passage 186 to the rearward end of the piston 182, the piston travels forward along the cylinder 178 until it impacts the anvil 177. A considerable amount of free travel is provided so that the piston 182 has a substantial velocity when it engages the anvil. Engagement of the piston 182 with the anvil 177 causes the anvil to move forward, and through the stripper lever 175 and push pins 163, drive the stripper ring 162 against the upper face of the blank 117 located in the dies. Since the kinetic energy of movement of the piston 182 must be absorbed in a very small stroke when the stripper ring 162 engages the blank head, sufficient forces are developed to stamp the required letters or numbers into the upper surface of the head. The valve controlling the air under pressure to the passage 186 is timed so that the stripper ring 162 impacts against the blank while the header slide 17 is in the forward dead center position.

To strip the blank 117 from the socketting tool 147 as the slide 17 moves back from the die breast 16, the stripper lever is rotated in a counterclockwise direction to push the pins 163 and in turn, the stripper ring 162 forward relative to the tool 147. This prevents the blank from being carried out of the dies by the tool. In FIGURE 13a a drive for the stripper lever is schematically illustrated. A link 191 is pivotally connected between the connecting rod 13 and an arm 192 on a cam shaft 193 journaled on the header slide 17. Therefore, the cam shaft 193 oscillates back and forth as the connecting rod 13 swings about its pivot on the header slide 17 in timed relationship to the reciprocating movement of the header slide. A cam 194 on the camshaft 193 engages the stripper lever 175 to produce the required counterclockwise movement thereof.

As the header slide 17 moves clear of the dies, the knockout pin 141 is pushed forward by the drive mechanism 74 to eject the finished blank at the die station 27, into the transfer fingers 23 which carry the finished blank to a position in alignment with the blank receiving station 28.

Located at the blank receiving station 28 is a tubular element 196 mounted in a holder 197 which is in turn, mounted in the header slide 17. The tubular member 196 is sized to receive the finished blanks 117 and is mounted in alignment with a tube 198 leading out of the header. In order to prevent the blanks from dropping out of the tubular member 196 as the header slide retracts, a spring loaded friction member 199 is mounted in the side of the tubular member 196 and pressed toward the blank by a leaf spring 201. Mounted in the die breast at the blank receiving station 28 is a pusher element 202 spring-biased toward its forward extreme position by a coil spring 203. As the header slide moves toward the pusher member 202, the blanks enter the tubular member 196 and are pressed therealong by the pusher member 202. The spring 203 is used to cushion the impact since there is a relatively long column of blanks contained in the tube 198.

A method and apparatus for forming socket-head cap-screw blanks incorporating this invention provides an improved shearing mechanism which eliminates islands in

the cut ends of the initial blank. The dies and tools cooperate with the shearing mechanism to form a finished blank having a head requiring no machining thereon thereby minimizing scrap, inventory costs and machine expense.

Although a preferred embodiment of this invention is illustrated, it is to be understood that various modifications and rearrangements of parts may be resorted to without departing from the scope of the invention as defined in the following claims.

What is claimed is:

1. A machine for producing blanks from cylindrical stock having a degree of ductility comprising a quill member, a cutter ring member, said members each being formed with a bore adapted to receive said stock, mounting means for moving said members from a first position in which said bores are aligned to a second position in which said bores are non-aligned, a curved cutting edge on each member at the end of its bore adjacent to the other of said members, the projection of each cutting edge on a plane through the axis of said bores and perpendicular to the direction of movement from said first position to said second position being curved, said projections being similar and opposed with the greatest spacing at the axis of said bores and curving toward each other at their extremities, said cutting edges being developed to space said projections apart a distance which is a direct function of the ductility of said stock, and means flowing the material of said blank adjacent to its end until such material is symmetrical about the central axis of such blank.

2. A cutter for shearing cylindrical stock having a degree of ductility comprising a quill member, a cutter ring member, said members each being formed with a bore adapted to receive and closely fit said stock, mounting means for moving said members from a first position in which said bores are aligned to a second position in which said bores are parallel and non-aligned, a curved cutting edge on each member at the end of its bore adjacent to the other of said members, the projection of each cutting edge on a plane through the axis of said bores and perpendicular to the direction of movement from said first position to said second position being curved, said projections being similar and opposed with the greatest spacing at the axis of said bores and a spacing less than said greatest spacing at their extremities, said cutting edges being developed to space said projections apart a distance which is a direct function of the ductility of said stock, said mounting means maintaining a space between said quill member and ring member.

3. A cutter for shearing cylindrical metal stock having a degree of ductility comprising a quill member, a cutter ring member, each member being formed with a bore being adapted to receive said stock, drive means supporting said members for movement from the first position in which said bores are aligned to a second position in which said bores are non-aligned, the adjacent ends of each member being formed with a concave recess intersecting the associated bore and extending across said member in a direction parallel to the direction of movement between said first and second position, the intersection of said recesses and associated bores defining opposed curved cutting edges axially spaced apart, said drive means maintaining an axial spacing between said quill member and cutter ring.

4. A method of shearing cylindrical metal stock comprising applying opposed shear forces to opposite sides thereof in a direction perpendicular to the axis of said stock, said shear forces being applied at curved zones spaced axially along said stock a distance which is a direct function of the ductility of said stock and the thickness of the stock in the direction of said shear forces whereby a plane of rupture between said zones is inclined relative to the axis of said stock.

5. A method of shearing cylindrical metal stock comprising applying opposed shear forces to opposite sides

thereof in a direction perpendicular to the axis of said stock, said shear forces being applied at curved zones spaced axially along said stock, the minimum axial spacing of said zones being located at the lateral extremities thereof with respect to said direction and being directly related to the ductility of the stock, the axial spacing at portions other than said lateral extremities being a direct function of the ductility of said stock and the thickness of said stock in the direction of said shear forces whereby a plane of rupture between said zones is inclined relative to the axis of said stock, said stock being supported against substantial bending on both sides of said plane of rupture.

6. A method of forming blanks comprising shearing a piece of stock from cylindrical metal stock by applying opposed shear forces to opposite sides thereof in a direction perpendicular to the axis of said stock, said shear forces being applied at curved zones spaced axially along said stock a distance which is a direct function of the ductility of said stock and the thickness of the stock in a direction of said shear forces whereby a plane of rupture between said zones is inclined relative to the axis of said stock, and thereafter laterally supporting said piece of stock in dies engaging the sides thereof to resist movement of said piece of stock axially relative to said dies, and pressing a tool against one end of said piece of stock moving said piece of stock along said dies with sufficient pressure exerted between said tool and said one end to square the piece of stock at said one end.

7. A method of forming blanks comprising shearing a blank from cylindrical stock by applying opposed shear forces to opposite sides thereof in a direction perpendicular to the axis of said stock, said shear forces being applied at curved zones spaced axially along said stock a distance which is a direct function of the ductility of said stock and the thickness of the stock in the direction of said shear forces whereby a plane of rupture between said zones is inclined relative to the axis of said stock, thereafter laterally supporting said blank and dies engaging the sides thereof adjacent one end to resist movement of said blank axially relative to said dies, and pressing a tool against said one end of said blank moving said blank along said dies with sufficient pressure exerted between said tool and said one end to upset said blank a point spaced from said one end and square said blank at said one end, and thereafter upsetting said blank in another die forming a head thereon at said one end.

8. A method of forming blanks comprising shearing a blank from cylindrical metal stock by applying opposed shear forces to opposite sides thereof in a direction perpendicular to the axis of said stock, said shear forces being applied at curved zones spaced axially along said stock a distance which is a direct function of the ductility of said stock and the thickness of the stock in the direction of said shear forces whereby a plane of rupture between said zones is inclined relative to the axis of said stock, and thereafter positioning one end of said blank in a sleeve engaging the side of said blank adjacent said one end and pressing the end of a tool against said one end within said sleeve while holding said sleeve against movement with said tool and exerting sufficient pressure between said tool at one end to form said one end to the shape of the end of said tool.

9. In a machine of the character described, a frame, a slide reciprocable relative to said frame, cutting means including a quill on said frame formed with a bore through which a cylindrical stock is fed and a cutting edge at the end of said bore, a cutter element reciprocable laterally relative to said quill, said cutter element being formed with a bore adapted to receive said stock and a cutting edge at the end thereof adjacent to said quill, said cutting edges on said quill and cutter element being formed by the intersection of the respective bores and a concave recess intersecting the associated bore and extending across said cutter element and quill in a direc-

tion parallel to the direction of movement of said cutter element relative to said quill whereby said cutter element severs blanks from said stock having ends inclined relative to the axis of said stock, a die station on said frame and slide receiving blanks from said cutting means, a fixed die on said frame at said die station receiving one end of said blank, a sliding die on said slide at said die station receiving the other end of said blank, a tool on said slide having an end movable along said sliding die, and means holding said sliding die stationary relative to said fixed die while said tool moves toward said fixed die pressing said other end along said sliding die and upsetting said blank between said dies, the friction between said other end of said blank and said sliding die resisting movement of said other end with said tool thereby producing a maximum pressure between the end of said tool and said other end of said blank.

10. A method of forming socket head cap screw blanks from cylindrical metal stock comprising applying opposed shear forces to opposite sides of said stock in a direction perpendicular to the axis of said stock, said shear forces being applied at curved zones spaced axially along said stock a distance which is a direct function of the ductility of said stock and the thickness of the stock in the direction of said shear forces whereby a plane of rupture between said zones is inclined relative to the axis of said stock, thereafter positioning said blank in a first die assembly engaging the side walls of said blank adjacent to one end thereof, upsetting said blank by pressing a tool against said one end and moving such tool relative to said die assembly, thereafter positioning said blank in a second die assembly with a cylindrical head cavity of uniform radius adjacent said one end and upsetting said one end into said head cavity with a tool shaped to form a crowned end face at said one end and unfilled corners at the inner end of said cavity, thereafter positioning said blank in a third die assembly having a cylindrical head cavity around said headed part of said blank and pressing a polygonal punch into said end face forming a polygonal socket therein, said punch forward upsetting the headed part into the inner corners of said third die assembly head cavity as the forward end of said punch moves past said crown and thereafter backward extruding said headed part along said punch in the associated die cavity.

11. A method of forming socket head cap screw blanks from cylindrical stock comprising applying opposed shear forces to opposite sides thereof in a direction perpen-

dicular to the axis of said stock, said shear forces being applied at curved zones spaced axially along said stock a distance which is a direct function of the ductility of said stock and the thickness of the stock in the direction of said shear forces whereby a plane of rupture between said zones is inclined relative to the axis of said stock, thereafter positioning the blank severed from said stock in a first die assembly engaging the side walls of said blank adjacent one end thereof, upsetting said blank and squaring said one end by pressing a tool against said one end and moving such tool relative to said die assembly whereby the engagement between said blank adjacent said one end and said die assembly resists movement of said end with said tool and concentrates pressure at said one end, thereafter positioning said blank in a second die assembly with a cylindrical head cavity of uniform radius adjacent said one end and upsetting said one end into said die cavity with a tool shaped to form a crown and a conical recess in the end face of said one end and unfilled corners at the inner end of said cavity, thereafter positioning said blank in a third die assembly having a cylindrical head cavity of uniform radius around the headed part of said blank and pressing a polygonal punch into said end face forming a polygonal socket therein, said punch forward upsetting the headed part into the inner corners of said third die assembly head cavity as the forward end of said punch moves past said crown and thereafter backward extruding said headed part along said punch in the associated die cavity.
